UNITED STATES PATENT OFFICE.

WILLIAM W. MUNSELL, OF CHICAGO, ILLINOIS.

FASTENING FOR LACINGS.

No. 899,888.

Specification of Letters Patent.

Patented Sept. 29, 1908.

Application filed November 20, 1905. Serial No. 288,161.

To all whom it may concern:

Be it known that I, WILLIAM W. MUNSELL, a citizen of the United States, and a resident of the city of Chicago, in the county of Cook and State of Illinois, have invented certain new and useful Improvements in Fastenings for Lacings, of which the following is a specification.

This invention relates to improvements in fastenings for lacings and particularly shoe lacings heretofore ordinarily fastened by tying the two ends of the lacings together when in their operative position for holding the shoe upon the foot and also to other fastenings in which the two ends are joined by a clip, permanent rivet or other devices.

The object of my invention is to provide a fastening for lacings and particularly shoe lacings which will entirely avoid the necessity of tying a knot in the lacing, which is not only uncomfortable to the wearer but frequently unreliable and unsightly, and which will enable the disposal of the ends of the lacing in such a manner that they will be out of sight and of no discomfort to the wearer.

A further object is a fastening for lacings adapted to be secured at any point between the extremities of the lacing uniting two parts of elastic and non-elastic lacings and which when in its operative position is not only sightly but ornamental.

A still further object of my invention is a fastening for lacings so constructed that the lacing may be conveniently inserted therein and which when clamped upon the lacing will hold it against any possible slipping and loosening in the shoe or other article containing the lacing.

A further object is a fastening for lacings and particularly shoe lacings adapted to hook, fasten and hold each one of two separate, distinct lacings in the same shoe and the non-elastic be connected with the other or elastic lacing in such a manner as to cause said separate lacings to appear and to be one and the same lacing.

With these ends in view, my invention consists in certain features of novelty in the construction, combination and arrangement of parts, by which the said objects and certain other objects hereinafter appearing are attained, all as fully described with reference to the accompanying drawings and more particularly pointed out in the claims.

In said drawings: Figure 1 illustrates a central vertical section of a fastening for

lacings embodying my invention. Fig. 2, a perspective view of the same in its operative position upon a shoe. Fig. 3, a central vertical section of a modified form of my invention attached in its operative position upon a shoe tongue. Fig. 4, a top plan view of Fig. 3 illustrates the possibilities of the ornamental character that the top of the screw of the fastener may have. Fig. 5, a vertical section of a modified form of the fastening illustrated in Figs. 1 and 3 and by which the lacings may be passed laterally between the clamping surfaces of the fastening. Fig. 6, a side elevation of my fastening with dotted lines indicating the relative position of the lacing strings in the fastening. Fig. 7, a detail front elevation of a shoe but may be of two pieces of leather for other purposes, illustrating the adaptability of the fastener shown in Fig. 1 as a connection between two separate and distinct lacings one part non-elastic and one part elastic and in such manner as to substantially conceal their distinctiveness.

Similar characters of reference indicate the same parts in the several figures of the drawings.

A. indicates the body or what may be termed the rigid jaw of a fastening for lacings containing my invention and which for convenience and appearance is preferably spherical in form and provided with a cored-out portion B. forming a passage for the lacing strings a to be clamped between the first and movable jaw of my fastening device.

The movable jaw of this device consists of a screw, threaded to work in the wall of the body of the device and between which and the bottom of said body or a superposed material laid therein, the lacings are confined and clamped in their operative position.

The outer end of the movable jaw C. is provided with a concavo-convex semi-spherical cap C. having an inner diameter greater than the body A. and when the movable jaw is in its operative position, extends sufficiently down over the body to conceal the same and present only to the eye the outer surface of the cap, which may be ornamented in any suitable manner attractive to the eye and for example, as illustrated in Fig. 4.

As the movable jaw and the fixed jaw of my fastening is preferably of metal and may be of hard rubber, it is desirable in order to provide against cutting the lacings and also preventing their slipping without the exer-

cise of too great pressure, that the pressing portion of the fixed jaw should have therein a yielding substance indicated at D. and which is preferably of rubber but may be of 5 felt and even wood, and which may be of rectangular form and recessed in the fixed jaw, as indicated in Fig. 1. The substance D may be provided with laterally extending flanges projecting towards its upper portion 10 beyond the base thereof, so as to afford a proper pressing surface for a correspondingly larger screw between which and the recess for yielding substance the proportion may be such that the outer edges of this larger clamping jaw may press against but a thin edge of 15 the elastic surface and therefore substantially against the harder substance of the fixed jaw, as shown at E. in Fig. 3.

The body or fixed jaw portion of my fastening is preferably provided with a laterally projecting hook, F formed integrally therewith through which the free ends of the lacings are passed and thereby held together and from dangling around and if long enough 25 thereafter tucked in position inside of the shoe out of sight.

The fastening illustrated in Fig. 1 is the preferred construction for men's shoes because there is so much of the length of the lacing 30 detachably held in hooks d, but after first loosening the lacing sufficient to detach the lacing from the hooks there is enough slack left in the lacing to loosen it sufficiently for removing the shoe without the necessity of 35 detaching the fastening from the lacing. In ladies' shoes however, which do not have these hooks, necessity requires the removal of the lacings from more or less of the eyelets every time such a shoe is put on and taken 40 off and this cannot be done without detaching the lacing fastening from the shoe.

For the purpose of ladies' shoes a modified form of my fastening is therefore shown in Fig. 3 in which the cored-out portion of the 45 fixed jaw is substantially enlarged laterally and the diameter of the movable jaw correspondingly increased and the fixed jaw provided with any suitable means which may be by forming a screw-threaded socket on the 50 inside thereof to receive a screw G. by means of which the fastening is secured to the tongue H. of a ladies' shoe, and whereby the fastening is not only secured to the shoe but in a convenient position for introducing and 55 withdrawing the lacings therefrom, as is readily permitted by the enlarged lateral opening.

In Fig. 5 I have shown a modification of the fixed jaw which consists in providing it 60 with an opening I. at one side thereof through which one or both lacings may be laterally introduced between the movable and fixed jaws of my fastening, instead of threading them through the cored-out portion, as required in the fastening shown in Figs. 1 and 3.

Fig. 6 by dotted lines, indicates the relative position of the lacings to each other and to the fixed and movable jaws when held thereby in their operative position.

A fastening for lacings, such as above described, is not only adapted for securing the lacing in its operative position by clamping its upper extremities, but for securing the lacings at any point between the two extremities of the lacing, as for example as 70 illustrated in Fig. 5, wherein is shown the adaptability of my fastening for a lacing, a lower part of which is non-elastic and the upper portion elastic, and in which it is particularly desirable to fasten the non-elastic 75 or lower portion of the lacing securely in its operative position without preventing the elastic upper portion from performing its function of enabling the upper portion of the shoe to yield to the muscular action of the 80 ankle and to various strains occurring in the wearing of a shoe and particularly when walking and running.

As shown in Fig. 7, the fastening is not only utilized to hold the non-elastic portion of 90 a lacing in its operative position but as a connection between the non-elastic and elastic portion of such lacing and for the purposes of a neat like disposal of the free and upper ends of the elastic portion, I practically employ a buckle J. which also serves as a means for taking up any undue slack in the elastic portion and thereby increasing and diminishing its tension, as may be desired.

When the non-elastic b and elastic portion 100 c of a lacing are each of a single separate piece, the fastening illustrated in Fig. 1 by means of the hook projection thereon, serves not only to hold the non-elastic portion of the lacing in its tightened position, but 105 to conceal the point between the non-elastic and elastic portions, as, illustrated in Fig. 7, and thereby present to the eye a seeming continuity between the two lacings when otherwise a more or less unsightly break 110 would appear, while at the same time the hook serves as an eye through which the elastic portion may freely move, as it will in efforts to equalize its tension on the part of both of its sides. In some instances however, one side of the elastic lacing may, by bending one of the lower hooks down upon it, be secured against detachment from the shoe but even when this is done there still remains the free movement of the lacing 115 through the hook whereby the lacing is enabled to adjust its tension as above described, for the reason that the relative position of the hook and the elastic lacing may be such that the hook will serve to prevent 120 the accidental detachment of the elastic lacing therefrom when not under tension but when under tension and in a stretched and therefore thinner condition, the lacing may 125 freely move through the hook itself, and 130

furthermore the curve or bend in the hook provides an eyelet to that end.

Having described my invention, what I claim as new and desire to secure by Letters 5 Patent is:

1. A fastening for lacings comprising in combination a fixed jaw provided with a cored-out portion forming a passage for lacings, and a movable jaw compressing and confining said lacing within said cored-out portion, said movable jaw being provided with a cap of a diameter greater than and concealing the fixed jaw beneath it, substantially as described.
- 10 2. A fastening for lacings comprising in combination a fixed jaw provided with a cored-out portion forming a passage for lacings and a movable jaw for clamping said lacings to the fixed jaw, said movable jaw being provided with a cap having a recess receiving the fixed jaw substantially as described.
- 15 3. A fastening for lacings comprising in

combination a fixed jaw provided with a cored-out portion forming a passage for lacings and a movable jaw for clamping said lacings to the fixed jaw, said movable jaw being provided with a concavo-convex cap into which the under side of fixed jaw projects substantially as described. 25

4. A fastening for lacings comprising in combination a fixed jaw provided with a cored-out portion, a hook laterally projecting from said jaw, and a rotatable jaw whereby the lacings are confined against movement 30 within said cored-out portion and the free ends of the lacing may be held together and separate lacings may be connected with each other, substantially as described. 35

In witness whereof, I have hereunto set 40 my hand this 16th day of November 1905.

WILLIAM W. MUNSELL.

In the presence of witnesses—

JNO. G. ELLIOTT,
M. S. REEDER.
